CLAIM

The ornamental design for a combination bottle cover and pet watering dish, as shown and described.

DESCRIPTION

FIG. 1 is an upright front perspective view of a combination bottle cover and pet watering dish in accordance with the present design;

FIG. 2 is an upright rear perspective view thereof;

FIG. 3 is a right side interior perspective view of the combination bottle cover and pet watering dish of FIG. 1, shown with a panel component detached;

FIG. 4 is an in-use perspective view of the combination bottle cover and pet watering dish of FIG. 1, shown in an upright open configuration; and,

FIG. 5 is an in-use perspective view thereof, shown in a horizontal position.

The broken-line disclosure in the above referenced figures illustrate an example intended environment for illustrative purposes only and forms no part of the claimed design.
